HYDRAULIC TYPE BARK-REMOVING MACHINE HAVING NOZZLE ADJUSTABLE ABOUT TWO SPACED HORIZONTAL AXES

Harry E. Bukowsky, Port Townsend, Wash., assignor to Crown Zellerbach Corporation, San Francisco, Calif., a corporation of Nevada

Application December 3, 1945, Serial No. 632,296

1 Claim. (Cl. 144—208)

1

This application is a continuation in part of my pending application, Serial No. 471,260, filed under date of January 4, 1943, and similarly entitled "Hydraulic log-barking machine," now U. S. Letters Patent No. 2,395,845, dated March 5, 1946.

An object of the present invention is to provide an improved hydraulic log-barking machine which can be used for logs of a wide range of diameters and in which the nozzle jet will strike the log surface approximately at a desired predetermined angle regardless of the size of the log.

A further object of the present invention is to provide a hydraulic log-barking machine in which adjustments in the position of the nozzle jet with respect to the log surface can quickly and easily be made, should this be found desirable.

In the accompanying drawings:

Fig. 1 is a fragmentary side elevation of my machine;

Fig. 2 is a fragmentary cross section taken on line 2—2 of Fig. 1, but drawn to a larger scale;

Fig. 3 is a fragmentary cross section similar to Fig. 2 but illustrating the debarking nozzle adjusted to a different position so as to enable the nozzle jet to strike the log at a different angle;

Fig. 4 is a similar sectional view illustrating the use of the machine with a log having an exceptionally rough and irregular surface;

Fig. 5 is a similar view illustrating the nozzle in another position; and

Fig. 6 is a diagrammatic figure illustrating how any desired nozzle jet direction will be maintained on logs of different diameters.

The log L (Fig. 1), after being properly positioned in my machine (by suitable means not shown), is supported at its ends by spur centers 10 and 11 carried on the ends of rotatable spindles, the spindles being mounted in thrust and radial load ball bearings. One of said spindles is carried in a slidable support 12, which is adjusted longitudinally with respect to the log. The other spindle is connected to driving means (not shown) whereby the spindle, and therewith the log, will be rotated at any desired speed.

The machine includes a rigid top frame 13 on which a carriage 14 (Figs. 1 and 2) is slidably mounted. Suitable means, such as a sprocket chain 15, connected to the carriage and operated

5 by sprockets and gears, preferably arranged as described in my co-pending application, Serial No. 471,260 (now U. S. Patent No. 2,395,845), with suitable clutches and controls, causes the carriage to travel longitudinally with respect to the log.

The carriage 14 (Fig. 2) has a downwardly extending bracket 16 at one side to which a nozzle arm 17 is pivotally attached. This nozzle arm 17 10 consequently moves up and down in a plane normal to the axis of rotation of the log. On the opposite or free end of the arm 17 a nozzle 18 is mounted. The nozzle 18 is pivotally supported on the arm 17 at 19 and carries a clamping screw 20, which passes through a curved slot 21 in the arm 17, by means of which the nozzle may be secured in different positions of angularity with respect to the log surface at any fixed position of the arm 17.

20 A guard or shoe 22, attached to the arm 17 by bolts 23, has a rounded bottom surface, as shown in Fig. 2, so that, if desired, the guard or shoe can ride on the surface of the log regardless of the direction of rotation of the log. The shoe 25 also protects the nozzle tip from any possible inadvertent contact with the log.

25 The nozzle 18 is connected by means of a suitable hose 24 to a pipe line 25. The pipe line 25 includes sections connected by swivel joints as 30 described in the above mentioned U. S. Patent No. 2,395,845. Water under hydraulic pressure is delivered through the pipe line and hose to the nozzle 18 and causes a debarking jet to be discharged from the nozzle tip.

35 A branch lever arm 26, integral with the arm 17, extends upwardly, as shown in Fig. 2, and is connected at its upper end to a pair of links 27 which in turn are connected to a guide block 28 attached to the end of a sliding bar 29. The 40 guide block 28 slides on a guide rod 30, and the sliding bar 29 slides in a support 31. A compression spring 32 is mounted on the sliding bar 29 and is held under compression between the support 31 and a washer 33, the washer in turn bearing against a pin 34 in the bar 29. A hydraulic cylinder 35, mounted in the carriage 14, has a piston rod 36, the outer end of which is enlarged and which bears against the end of the sliding bar 29. A suitable piston within the 45 hydraulic cylinder 35 is connected to the piston

rod 36 and a control valve and ports (not shown) at the ends of the hydraulic cylinder enable the piston rod 36 to be moved in either direction as desired.

From Fig. 2 it will be apparent that when the piston rod 36 is moved to the right (as viewed in Fig. 2) the free end of the arm 17, and with it the nozzle 18, will be raised. The raising of the arm 17, however, will increase the compression of the spring 32. If the arm 17 is so positioned that the guard or shoe 22 rides on the surface of the log, the spring 32 will hold the guard against the log surface but will nevertheless permit the guard and arm to be pushed upwardly if this is required by the irregularity of the log surface. The spring 32 should of course be strong enough to prevent the arm 17 from being pushed upwardly by the reaction or kick-back which would ordinarily be produced by the discharging of the debarking jet from the nozzle, especially if the nozzle is positioned as shown in Figures 3 and 4. Instead of the combination of the hydraulic cylinder 35 and compression spring 32 which I use for positioning the arm 17, other means could be used, but the means shown is simple and practical.

In Fig. 2 the guard or shoe 22 is shown resting on the log surface and the nozzle 18 is so directed that the jet will strike the log surface at substantially the same angle as shown in my U. S. Patent No. 2,395,845. The log in this arrangement is rotated counter-clockwise, as indicated by the arrow X.

In Fig. 3, the nozzle 18 is shown in another position so that the jet is directed differently, and the log is rotated in clockwise direction. Fig. 5 illustrates still another position of the nozzle and nozzle jet. For different types or kinds of logs it may be desired to change the angle of impingement of the nozzle jet with respect to the log surface, and in such case this can easily be done by means of the clamping screw 28. However, with the nozzle clamped in a predetermined desired position the angle of impingement of the jet with respect to the log surface will be substantially the same regardless of the log diameter, due to the fact the pivotal mounting of the arm 17 and the nozzle tip are located in different quadrants.

This is diagrammatically illustrated in Fig. 6, in which 40, 41 and 42 indicate logs of different diameters, and 43 indicates the pivotal point of the nozzle-carrying arm. For any fixed position of the nozzle on the supporting arm the center line of the nozzle jet, indicated by the lines 44, 45 and 46, will be a tangent to an imaginary circle with 43 as its center, such as the circle 47. It will be apparent that the angles which the lines 44, 45 and 46 make with the tangents to the circles 40, 41 and 42 respectively, thus the angles, a, b and c are substantially the same.

When the log surface is very rough it may be preferable to position the nozzle arm so that the guard or shoe 22 will be slightly spaced from the log surface, as shown in Fig. 4. Also, if desired, the nozzle arm can be used without the guard or shoe, as shown in Fig. 5. However, under most conditions it is safer to have the guard or shoe attached to avoid damage to the nozzle tip and associated parts if the nozzle should accidentally come into contact with a protrusion, such as a knot, on the log surface.

Various modifications within the scope of my invention could be made in the device which I have shown. It is not my intention to limit my invention otherwise than as stated in the claim.

I claim:

In a hydraulic log-barking machine, means for supporting a log for rotation, a carriage movable in a plane parallel to the rotational axis of the log, means for rotating the log, means for moving said carriage longitudinally of the log, a nozzle-carrying arm pivotally mounted on said carriage for movement in a plane substantially normal to the rotational axis of the log, a debarking nozzle adjustably mounted on said arm and movable about an axis parallel to said rotational axis, means on said arm and nozzle to secure said nozzle in any selected position of adjustment, said nozzle connected with a source of water under pressure, said nozzle having a tip discharging a jet downwardly and located adjacent the axis about which said nozzle can be adjusted, whereby adjustment of the nozzle changes the direction of a jet of water discharging from said tip but does not appreciably change the distance between said tip and the log means associated with said arm for moving said arm on its pivotal mounting, and thereby positioning said nozzle tip at any desired distance from the surface of a log in said machine, the pivotal mounting of said arm and the discharging tip of said nozzle being located over opposite sides of the log, whereby a selected nozzle jet direction with respect to the log surface is automatically maintained for logs of various diameters.

HARRY E. BUKOWSKY.
